UNITED STATES PATENT OFFICE.

MARCELLUS F. BERRY, OF BROOKLYN, NEW YORK.

FILE-BINDER.

SPECIFICATION forming part of Letters Patent No. 398,574, dated February 26, 1889.

Application filed June 18, 1888. Serial No. 277,406. (Model.)

To all whom it may concern:

Be it known that I, MARCELLUS F. BERRY, of Brooklyn, in the county of Kings and State of New York, have invented a new and useful Improvement in File-Binders, of which the following is a specification.

The object of my invention is to provide improved, simple, and effective means for binding together, with or without stiff or flexible covers, files of papers, such as newspapers, magazines, and other periodicals, or circulars, bills, law or other papers which it may be desirable to preserve for ready or future reference.

15 The improvement will be hereinafter fully described with reference to the accompanying drawings, and its novel features will be pointed out in the claims.

Figure 1 represents a plan view of parts of two rigid covers united by a flexible back and having attached a binder embodying my invention and containing a file of papers. Fig. 2 represents a transverse section on line $x-x$ of Fig. 1. Fig. 3 represents a longitudinal view, the greater part in section, on line $y-y$ of Fig. 2. Fig. 4 is a perspective view of the point-clamp bar and needles of Figs. 1, 2, and 3. Fig. 5 represents a plan view of a part of a file of papers without covers and a binder having my improvement, by which the said papers are bound together. Fig. 6 represents a longitudinal sectional view of Fig. 5. Fig. 7 represents a plan view of a part of a file of papers without covers and a binder embodying my invention, distinguished from Fig. 5 by a modification in the details of binder. Fig. 8 represents a longitudinal sectional view of Fig. 7. Fig. 9 represents a plan view of a part of a file of papers, the sheets of which are held together by a binder embodying my invention in a further modified form. Figs. 10 and 11 are plan views of files of papers with covers and binders embodying my invention still further modified in its details. Fig. 45 12 represents a perspective view of a single needle and a point-clamp bar therewith.

Like letters of reference indicate corresponding parts in all the figures.

A indicates a pliant metallic needle, preferably a piece of flattened annealed brass wire,

of sufficient length to provide for firmly attaching the head to a head-clamp bar, B, and for passing through the file of papers to be bound together and for bending over upon the same. For convenience I will designate 55 and refer to that side of a file of papers through which the needle enters as the "lower" side, and to the opposite side through which the point of the needle emerges as the "upper" side.

C indicates a point-clamp bar grooved on 60 its under side to receive the point of the needle A, and having a portion of the said groove closed or contracted to pass under the needle and retain it in the groove. The closed 65 or contracted part of the groove is indicated by the letter a.

For binding narrow sheets of paper together—as, for example, blank checks, bills, or receipts—by their stub ends, a single needle, 70 A, may be employed, as represented in Figs. 10 and 11; but when the papers of the file are of considerable width—as newspapers or periodicals, for example—two or more needles, A, may be employed with a single head-clamp 75 bar, B, to which the several needles are firmly attached, and a single point-clamp bar to receive the several points, as represented in Figs. 3, 6, and 8.

When no rigid cover is employed between 80 the point-clamp bar C and the upper papers of the file, an intermediate clamp-plate, D, may be inserted beneath the bent-over parts of the needle above the file to stiffen the binding, and stiff or rigid covers b b, united by a 85 flexible back, c, may be neatly attached outside the binding, so as to conceal from view the details thereof by flexibly attaching the head-clamp bar B in the form of a stub to the inner edge of one cover, b, and also attaching the intermediate clamp-plate, D, in the 90 form of a stub by a similar flexible connection to the other cover, b, as represented in Figs. 1, 2, 3, 10, and 11.

In Figs. 1, 2, 3, and 4 the head-clamp bar B 95 and the intermediate clamp-plate, D, are both represented as formed of similar flat thin metallic bars, or plates extending nearly the whole length of the file and covered with cloth or flexible material, the inner edges of 100

which are neatly attached to the respective covers, forming flexible connections *g* therewith.

In Figs. 3, 6, and 8 the heads of the needles are represented as firmly attached to the head-clamp bar by a loop or bend, *e*, in the head of the needle, which incloses a portion of the bar. In Fig. 3 two holes, *d d*, are represented made through the head-clamp bar at a short distance apart, and the head of the needle passes down through one hole *d* and up through the other and is bent over upon the portion of the bar between the two holes *d d*, thereby inclosing that portion in the loop or bend *e* thus formed. In Figs. 6 and 8 the head-clamp bar *B* is represented as formed of thin metal and grooved upward, and at the point where the head of the needle is firmly attached thereto portions of the metal on opposite edges of the groove are bent inward toward each other and the bends *e* of the needles inclose these inwardly-projecting portions *f* of the head-clamp bars *B*.

In order that the point-clamp bar *C* may be securely retained in position after being placed over the points of the needles, as hereinbefore set forth, I employ an elastic or spring catch or holder, *E*, attached to said head-clamp bar, which engages or is attached to some fixed point or portion of the file or binder.

In Figs. 1, 3, 4, 11, and 12 the holder *E* constitutes an extension of one extremity of the point-clamp bar *C*, flattened and bent at the point in order that when the bar *C* is in position the point of the flattened end of the bar *C* will spring down over the end of intermediate plate, *D*, and prevent the bar *C* from moving in the direction of the points of the needles.

In Figs. 5 to 9, inclusive, the holder *E* is represented as formed of a flattened wire spring, one end of which is firmly secured to the top of the point-clamp bar and the other end of which is bent down at right angles, and the part thus bent down passes through a hole in the point-clamp plate and into the hole in the file through which the needle passes.

In Figs. 5 and 6 one point of the flat spring of the holder *E* is fastened to the top of the point-clamp bar by having its point turned down into a hole, *h*, in the bar *C*, and is guided and passed into or released from the hole in the file by a sliding ring or clamp, *i*, through which it passes, and which may be moved back and forth, sliding upon the bar *C* for the said purpose.

In Figs. 7, 8, and 9 the flattened wire spring of the holder *E* passes through a hasp, *j*, on the top of the bar *C*, and is bent on both sides of hasp *j* to prevent it from moving endwise and so that its bent-down point will be held down in the hole in the file when the bar *C* is in position.

In Fig. 10 the holder *E* consists of an elas-

tic cord attached at one end to the end of bar *C* and at the other end to a fixed point in the cover *b*.

In all the figures except Fig. 11 a portion 70 or portions of the grooves in the bar *C* are contracted or closed to pass under and retain the needles by driving or bending short portions of the edges of the grooves toward each other. In Fig. 11 a portion of the groove is 75 closed by cutting across the middle of bar *C* two holes or slots and forcing the part between the holes downward a sufficient distance to close the groove and permit the needle to pass above the part thus forced down and lie in 80 the groove on either side.

What I claim as new, and desire to secure by Letters Patent, is—

1. In a file-binder, the combination, with a pliant metallic needle to pass through the file 85 of papers and bend over thereon and bind the same, of a head-clamp bar, to which the needle is firmly attached, and a point-clamp bar grooved to receive the point and having a portion of the said groove closed or contracted to pass under and retain the needle, substantially as described and set forth.

2. In a file-binder, the combination, with a pliant metallic needle to pass through the file of papers and bend over thereon and bind 95 the same, of a head-clamp bar, to which the needle is firmly attached, a point-clamp bar grooved to receive the point and having a portion of the said groove closed or contracted to pass under and retain the needle, 100 and an intermediate clamp-plate beneath the bent-over parts of the needle to stiffen the binding or attach to a cover, all substantially as described and set forth.

3. In a file-binder, the combination, with a 105 pliant metallic needle to pass through the file of papers and bend over thereon and bind the same, and a head-clamp bar, to which the head of the needle is firmly attached by a loop or bend therein inclosing a portion of 110 the bar, of a point-clamp bar grooved to receive the point of the needle and having a portion of the said groove closed or contracted to pass under and retain the needle, substantially as described and set forth. 115

4. In a file-binder, the combination, with a pliant metallic needle to pass through the file of papers, bend over thereon and bind the same, and a head-clamp bar, to which the head of the needle is firmly attached, of a 120 point-clamp bar grooved to receive the point and having a portion of said groove closed or contracted to pass under and retain the needle, and an elastic catch or holder to retain the point-clamp bar on the needles, substantially as described and set forth.

5. In a file-binder, the combination, with a pliant metallic needle to pass through the file of papers, bend over thereon and bind the same, a head-clamp bar, to which the needle 125 is firmly attached, a point-clamp bar grooved to receive the point and having a portion of

said groove closed or contracted to pass under and retain the needle, an intermediate clamp-plate beneath the bent-over parts of the needle, of two covers and a flexible back, 5 one of said covers being flexibly attached to the head-clamp bar and the other cover being flexibly attached to the intermediate clamp-

plate, all substantially as herein described and set forth.
